ATTORNEYS

UNITED STATES PATENT OFFICE.

GEORGE H. ENNIS, OF DERBY, CONNECTICUT.

AUTOMATIC TRAIN-STOPPING DEVICE.

1,178,305.

Specification of Letters Patent. Patented Apr. 4, 1916.

Application filed December 15, 1914. Serial No. 877,313.

To all whom it may concern:

Be it known that I, GEORGE H. ENNIS, a citizen of the United States, and a resident of Derby, in the county of New Haven and 5 State of Connecticut, have made certain new and useful Improvements in Automatic Train-Stopping Devices, of which the following is a specification.

My invention relates to improvements in 10 automatic train stopping devices and it consists in the combinations, arrangements, and constructions herein described and claimed.

An object of my invention is to provide 15 magnetic means for stopping a train in which there is no actual contact between the devices carried by the engine and those distributed along the track.

A further object of my invention is to 20 provide a device of the type described in which the magnetic devices which are distributed along the track act upon an armature in such a manner as to release a weight, the release of the weight serving to actuate the throttle lever, the brake lever, to blow 25 the whistle, or to actuate electrical mechanism for the controlling of the motor, in case electricity should be used instead of steam.

A further object of my invention is to 30 provide a device having a magnetically operated trip in which a minimum of magnetic force is necessary.

A further object of my invention is to 35 provide a device having an armature so arranged as to insure the operation of the train stopping mechanism no matter how fast the train is going.

Other objects and advantages will appear 40 in the following specification and the novel features of the device will be particularly pointed out in the appended claims.

My invention is illustrated in the accompanying drawings forming part of this application in which—

45 Figure 1 is a face view of the device, certain parts being shown in section, Fig. 2 is a diagrammatic view showing the arrangement of the magnets on the track and the means for energizing the same, and Fig. 50 3 is a section along the line 3—3 of Fig. 1.

In carrying out my invention I make use of ordinary track rails such as those shown at 1 and 2 in Fig. 2. Secured to the outer side of the rail, by any suitable means such 55 as plates 3 and bolts 4 is a series of magnets 5. As will be seen from the drawings these

magnets are arranged with their poles extending upwardly, the ends of the poles being in alinement. The magnets are preferably arranged at the ends of the track sections. Thus in Fig. 2 the end of section A is separated from the section B at the points x.

Carried preferably by the body 6 of the engine cab is a plurality of downwardly 65 extending U-shaped brackets 7 which may be secured by means of bolts 8 or in any other suitable manner. In Fig. 1 I have shown two of these brackets, but it will be understood that as many may be provided as is necessary. Arranged to extend through 70 threaded openings 9 in the bottom portions of the brackets is a bolt 10. The lower part of this bolt is smooth and extends through an opening 11^a in an armature 11. Bosses 75 such as that shown at 12 are provided for giving an extended bearing to the engaging portion of the bolt 10. Each of the brackets is provided with a bolt 10 arranged to extend through an opening in the armature 80 11 similar to that already described. A cross bar 13 is also threaded to receive the bolts 10 and is provided with an opening 14. Nuts 15 may be screwed on the ends of the bolts 10 so as to hold the cross bar 13 in 85 position, the bar forming a brace for the brackets 7.

Secured to the body 6 of the cab is a casing 16 having at its lower end a dash pot 17 having a small opening 18 for the escape 90 of air. A frame 19 is disposed within the casing upon which may be mounted weights 20. The frame has a downwardly extending rod 21 which passes through the end of the casing 16 and which is provided with a 95 plunger 22 arranged to reciprocate in the casing 17 and which forms part of the dash pot. To the upper end of the frame 19 are connected the flexible cables 23, 24 and 25. The former runs over an idler 26 and is 100 connected with the throttle lever 27 which has the usual locking segment 28. The cable 24 passes over the idler 29 and is secured to the brake lever 30 which is acted on by a spring 31. The cable 25 may extend to 105 a whistle or to an electric switch (not shown) for operating these devices on the movement of the weight 20.

Secured to the bottom of the body portion 110 6 of the cab is a plate 32 upon which a lever 33 is pivoted on a fixed pivot 34. The plate 32 bears a lower stop member 35 and

an upper stop member 36 secured to the body portion of the cab. The lever 33 is normally acted on by a tension spring 37.

On an arm 38 carried by the casing 16 is pivotally mounted a bell-crank lever 39 which has its fixed pivot at 40. The bell-crank lever 39 is in turn connected with a lever 41 at 42, the lever 41 being connected with a lever 43 at 44 and the lever 43 being pivotally mounted on a fixed lug at 45. A link 46 connects the point 44 by means of a pivotal connection 47 to the lever 33.

From the foregoing description of the various parts of the device the operation thereof may be readily understood.

The magnets, as before stated, are arranged preferably at the ends of the track section, but they may be arranged at any point along the track at which it is desired to stop the train automatically. In Fig. 2, I have shown a means by which the magnets may be energized. This is merely for the purpose of illustration, since the magnets may be energized by closing a switch manually or in any other way. In Fig. 2 I have shown the semaphore arm 47 as having a contact 48 connected by a conductor 49 with a battery B and when in the clear position, as shown in Fig. 2, it is out of engagement with a contact 50 connected to a conductor 51. The battery is connected to a lead wire 52 while the conductor 51 is connected with a lead wire 53. As will be seen from this drawing the magnets are arranged in parallel, being connected to the lead wires 52 and 53. Now when the semaphore is brought up into the danger position contact is made at 48-50 and current will flow from the battery through 49, 48, 50, 51, 53, through the magnets 52 and back to battery B, thus energizing the magnets.

The apparatus on the engine is set, as shown in Fig. 1. It will be noted that the frame 19 bearing the weights 20 is held in an upper position by means of the bell-crank lever 39 which projects through an opening 18 in the casing 16. The frame 19 cannot be moved downwardly because the bell-crank lever is held in this position, since the points 42, 44 and 45 are in alinement. The levers 41 and 43 form a toggle joint arrangement. When now the joint is flexed, the bell-crank lever 39 will swing out of the way of the frame 19 bearing the weights 20 and the latter will descend. Suppose now the train with the apparatus set reaches the point where the armature 11 will pass just above the magnets 5. The armature will be drawn downwardly, thus pulling on the core 54 and by means of the lever 33 and link 46 it will move the levers 41 and 43 into the dotted line position shown in Fig. 1, thus flexing the joint and causing the retraction of the bell-crank lever 39 whereupon the weight in the frame 19 will cause the latter

to descend. The rapidity of this action is governed by the construction of the dash pot, the opening 18 being such as to time the action properly in connection with a given weight in the frame. The downward movement of the frame 19 will cause the operation of the throttle lever and also the brake lever and may cause the blowing of the whistle, or if the device is equipped with electrical controlling means, as for instance where the engine is an electric engine and not a steam engine, the cable 25 may be caused to actuate the controlling means so as to stop the train. In order to reset the apparatus it is only necessary to lift upwardly on any of the cables connected with the frame 19 bearing the weights 20, for when the end of the frame has cleared the end of the bell-crank lever 39, the spring 37 acting on the lever 33 will again bring the toggle joint into such position that the points 42, 44 and 45 will again be in alinement so that the frame may then be rested on the bell-crank lever without any danger of flexing the toggle joint. It will be understood, of course, that the cables will have sufficient slack to permit the operation of the various levers such as the throttle lever and brake lever without movement of the frame, but that when the frame is permitted to drop it will operate the throttle lever so as to stop the train and operate the brake lever so as to set the brakes. This is a mere matter of adjustment. The drawing is merely for the purpose of illustrating the operation and is not intended to be drawn to scale. It is necessary only to move the bell-crank lever 39 far enough to permit the frame 19 to drop. The stop 32 may be used to limit the movement of the toggle joint device.

It will be noted that there is no actual contact between the magnets and the armature. It will also be noted that the throttle lever and brake lever, whistle, etc., are operated by gravity, the magnetic device being merely used to trip the frame 19 bearing the weights 20. Obviously more or less weights can be placed in the frame 19 and a spring 37 having greater or less tension may be used to restore the weight-holding device to its normal position, these details being a mere matter of experiment under given conditions.

I claim:

1. The combination with a track having a series of magnets disposed beside the rails, of an engine having train-controlling devices, brackets carried by said engine, adjustable bolts carried by said brackets, an armature movable toward and away from the track rails, and being guided in its movement by said bolts, a casing secured to said engine body, a vertically slidable frame disposed within said casing, and arranged to

carry weights, means including a trip for holding said frame in an upper position, a flexible cable connected with said armature and having operative connection with said⁵ trip for holding said armature in an upper position, the passage of the engine above said magnets serving to attract the armature thereby releasing the trip and permitting the frame to fall, and flexible cables connected with said frame at one end and with said controlling devices at the other.

2. The combination with a track having a series of magnets disposed beside the rails, of an engine having train-controlling devices, brackets carried by said engine, adjustable bolts carried by said brackets, an armature movable toward and away from the track rails, and being guided in its movement by said bolts, a casing secured to

said engine body, a vertically slideable frame 20 disposed within said casing, and arranged to carry weights, means including a trip for holding said frame in an upper position, a flexible cable connected with said armature and having operative connection with 25 said trip for holding said armature in an upper position, the passage of the engine above said magnets serving to attract the armature thereby releasing the trip and permitting the frame to fall, flexible cables connected with said frame at one end and with said controlling devices at the other, and means for controlling the time of descent of the frame. 30

GEORGE H. ENNIS.
